UNITED STATES PATENT OFFICE

JOE S. FELSHIN, OF NEW YORK, N. Y.

DESIGN FOR A BOOKCASE

Application filed May 29, 1928. Serial No. 26,904. Term of patent 3½ years.

To all whom it may concern:

Be it known that I, JOE S. FELSHIN, a citizen of the United States, and resident of New York city, in the county of New York and State of New York, have invented a new, original, and ornamental Design for Bookcases, of which the following is a specification, reference being had to the accompanying drawing, forming part thereof, in which the figure is a perspective view of a bookcase, showing my design.

I claim:

The ornamental design for a bookcase, as shown.

Dated May 25, 1928.

JOE S. FELSHIN.
